UNITED STATES PATENT OFFICE.

KARL MUHLEISEN, OF PHILADELPHIA, PENNSYLVANIA, ASSIGNOR TO SCHUTTE AND KOERTING COMPANY, OF PHILADELPHIA, PENNSYLVANIA, A CORPORATION OF PENNSYLVANIA.

FLUID-HEATING DEVICE.

Application filed December 20, 1924. Serial No. 757,112.

My invention relates to devices for heating fluids, particularly liquids, such as water, oil and the like, and it has for its general object to provide a novel device having means whereby great efficiency is obtained in proportion to the energy expended.

It is also an object of the invention to provide a device having a novel construction of means whereby a maximum quantity of fluid may be heated in a minimum of time within a relatively small space.

A further object of the invention is to provide a heating device of novel construction comprising a plurality of spiral passageways arranged in superposed relation to each other, one of the said passageways being arranged so that the liquid flows therethrough in a direction opposite to that in which it flows in the other passageway.

Another object of the invention is to provide a heating device comprising a couple of disc-like members each of which is provided with one or more spiral grooves in one side thereof, which discs are adapted to be secured together with the said grooves in opposed relation to each other and separated from each other by a sheet of suitable material which cooperates with the said grooves to form closed spiral passageways.

A still further object of the invention is to provide a heating device comprising a plurality of heating units arranged in superposed relation to each other.

No attempt has been made to point out all of the objects and advantages which are incident to the invention but in the detailed description thereof which follows other objects and advantages of the invention will be specifically referred to or will be apparent therefrom.

In order that the invention may be readily understood and its practical advantages fully appreciated, reference should be had to the accompanying drawing in which I have illustrated certain convenient forms of embodiment of the same. However, it will be understood that the invention is susceptible of embodiment in other forms of construction than those shown, and that changes in the details of construction may be made within the scope of the claims without departing from the said invention.

In the drawing:

Fig. 1 is a central vertical sectional view

of a portion of a heating device comprising heating units embodying the invention;

Fig. 2 is a horizontal sectional view taken on the line 2—2 of Fig. 1;

Fig. 3 is a plan or face view of one of the elements or members of a heating unit;

Fig. 4 is a plan or face view of a plate which is interposed between oppositely disposed members of a heating unit;

Fig. 5 is a view partly in horizontal section and partly in top plan of a heating unit;

Fig. 6 is a view in central vertical section showing a modified construction of a heating device embodying the invention;

Fig. 7 is a view partly in horizontal section and partly in top plan of the device shown in Fig. 6;

Fig. 8 is a plan view of the inside face of one of the oppositely disposed members of the said device;

Fig. 9 is a plan or face view of a plate, adapted to be interposed between said members; and

Fig. 10 is a top plan view of one of the said oppositely disposed members.

Referring to the drawing: 1 designates a casing of heat insulating material within which a plurality of heating devices are adapted to be placed one above the other as illustrated in Fig. 1. The insulating material 1 is surrounded by an outside covering or casing 2 of metal.

Referring to Figs. 1 to 5 inclusive of the drawing, it will be noted that each of the heating devices comprises disc-like members 3 and 4.

The disc-like members 3 and 4 are provided respectively with spiral grooves 5 and 6 upon the oppositely disposed surfaces thereof, and plate 7 is interposed between and separates these members as is clearly shown in Fig. 1. The members 3 and 4 are secured together by means of a plurality of bolts 10 which extend through openings near the peripheries thereof. The said members are clamped against the opposite sides of the plate 7 so as to clamp and hold the same in stationary position therebetween.

The member 3 is provided with an opening 12 which extends from the periphery thereof and communicates at its inner end with the outer end of the spiral groove 5. The inner end of said groove terminates in an en-

larged opening 15 at the center of the disc 3. The inner end of a pipe 16 is secured in the outer end of the passageway 12. The fluid such as oil or water to be heated flows from the pipe 16 through the passageway 12 into the passageway 5, which by reason of the presence of the plate 7 is a closed passageway and flows therethrough into the enlarged opening 15. From the latter the liquid flows through an opening 20 at the center of the plate 7 into a recess 21 at or near the center of the disc-like member 4. From the latter the liquid is conducted through the closed passageway 6 to the outer end thereof from which it escapes through a passageway 22 to the peripheral edge of the member 4 thence through a pipe, a portion of which is shown at 23, to its destination, not shown. It will be observed that the inner end portions 16 and 23 of the pipes extend through the casing composed of the portions 1 and 2. It will be observed that the outer sides of the disc-like members 3 and 4 are cut away to form relatively large recesses 25 and 26. Within these recesses the means for heating the discs 3 and 4 and the liquid which is caused to flow through the passageways 5 and 6 previously referred to is mounted. In the construction as shown electric heating means is provided. Each heating unit comprises a disc or block of insulating material 27 within the inner surface of which a spiral groove 28 is provided. Within the said groove resistance coils 30 are located which upon the passage of electric current therethrough become heated. The heating of these coils operate to heat the discs 3 and 4, the heat of which is transmitted to the liquid as it flows through the passageways 5 and 6 so as to heat the same. The insulating discs or blocks 27 are secured to the plates 3 and 4 by means of screw bolts 31 as shown. It will be noted that the passageways 12 and 22 are located in diametrically opposed position with respect to each other. It will be understood, however, that if desired the disc-like members 3 and 4 may be adjusted with relation to each other so as to change the position of the said openings 12 and 22 with respect to each other as is indicated in Fig. 5 of the drawing. In such case it will be understood that the necessary changes in the positions of the openings through the casing comprising the parts 1 and 2 must be made. Such adjustment of the disc-like members 3 and 4 with respect to each other obviously is rendered possible because of the fact that communication from the passageway 5 to the passageway 6 is effected through the opening 20 at the center of the plate 7. This being the case it is clear that the disc-like members 3 and 4 may be rotatively adjusted relatively to each other so that the positions of the pipes 16 and 23 with respect

to each other may be altered as may be desired. This is a desideratum greatly to be desired in some cases where because of obstructions which may be present the location of the inlet and outlet openings in diametrical relation to each other as is shown in Figs. 1 and 2 is prevented. 70

As is indicated in Fig. 1 of the drawing, a plurality of fluid heating units comprising the parts or elements 3, 4, 7, etc., may be placed in superposed relation to each other, as is shown, within the chamber formed by the casing comprising the parts 1 and 2. The heating units are separated from each other by means of a disc or diaphragm 33 which preferably should be of insulating material. 75

In the construction as thus far described I have provided in each of the disc-like members 3 and 4 a single spiral groove, but if desired a couple of spiral grooves arranged in parallel or side by side relation to each other may be provided. In one face of each of the said disc-like members in Figs. 6 to 10 inclusive of the drawing I have shown a construction of the latter kind. 80

The parts 10, 12, 16, 22, 23, 25, 27, 28, 30 and 31 shown in said figures are identical with the parts correspondingly numbered in Figs. 1 to 5 inclusive of the drawing. 85

In the said Figs. 6 to 10 inclusive the disc-like members 3^a and 4^a are secured together by the bolts 10 and are separated from each other by a plate 40 of metal or other suitable material. The disc-like member 3^a is provided with a couple of spiral passageways 41 and 42. The outer end of the former is in communication with the inlet opening 12 and its inner end is in communication with an enlarged opening 43 at the center of the disc-like member 3^a. The inner end of the passageway 42 is in communication with the said enlarged opening and the outer end thereof terminates or merges into a groove 44 which is concentric with the center of the disc-like member 3^a. The fluid, such as water, oil or the like, flows from the groove 44 through openings 45 near the periphery of the plate 40 into a concentric groove 46 in the disc-like member 4^a, which groove is located in oppositely disposed relation to the groove 44. The fluid having entered the groove 46 flows along the spiral passageway 47 and is discharged at the inner end thereof into an enlarged opening 48, and from the latter enters the inner end of a spiral passageway 50 and flows outwardly therethrough from which it is discharged through the passageway 22 which leads to the periphery of the disc-like member 4^a and is in communication with the outlet pipe 23. By providing a couple of grooves in side by side relation to each other in the inner side of each of the disc-like members 3^a and 4^a, the length of the passageway 110

115

120

125

130

through the heating unit through which the fluid, such as water, oil or the like, must flow is increased and consequently the period of time during which it is subjected to the action of the heating element is increased.

By providing the concentric grooves 44 and 46 near the peripheries of the disc-like members 3^a and 4^a I am enabled to rotatively adjust the said members with respect to each other so that the inlet and discharge openings 12 and 22 need not be located in diametrically opposite positions with respect to each other as shown in Figs. 6 and 7, but may be angularly related to each other the same as is the case in the construction disclosed in Figs. 1 to 5 inclusive.

It will be understood that when a plurality of heaters or heating units are arranged one above the other as indicated in Fig. 1 the inlet pipes may be connected with and supplied from a single supply pipe and that the outlet pipes leading from the respective units may be connected with and discharged through a single discharge pipe.

It will be also understood that the heating coils of all of the units may be supplied with electric current from a single or common source. I have not shown the single supply and the single discharge pipe or the means for supplying electric current from a single source because these features of construction are common mechanical expedients and constitute no part of my invention.

It will be understood that by my invention I have provided a heater or heating unit which is of simple construction and which is highly efficient; also that I have provided a construction of heater which is of flattened formation so that it is well adapted to constitute and form a part of a battery of heaters or heating devices such as that indicated in Fig. 1 of the drawing, where it is desired to heat at one time a greater volume of fluid than may be heated by a single unit. By increasing the number of units the volume of fluid which may be heated at one operation or at one time may be increased as desired.

Having thus described my invention, what I claim and desire to secure by Letters Patent is:

1. A heating device comprising members secured together in oppositely disposed relation to each other, the opposing sides of said members being provided with grooves therein, means interposed between the said members and seated against the edges of said grooves to close the same, the said means having a passageway therethrough at its center whereby the passageway in one of the said members is in communication with the passageway in the other said member, and electrically heated coils located in contiguous relation to the outer sides of said members for heating the same to effect heating

of a fluid as it flows through said passageways.

2. A heating unit comprising disc-like members each of which is provided with a spiral groove upon its inner side, a plate located between the said disc-like members which plate is adapted to contact with the edges of said grooves and convert the same into closed passageways, the said plate having an opening therethrough at its center, means for securing the said disc-like members together and clamping the said plate between the same, means for supplying a fluid to the outer end of one of the said passageways, which fluid is adapted to flow through the opening through said plate into the passageway in the other of said disc-like members, means for conveying the fluid from the outer end of the said last-named passageway, and electrically heated coils located in contiguous relation to the outer sides of said disc-like members for heating a fluid as it flows through the said spiral grooves.

3. A heating unit comprising a plurality of members secured together, each of said members being provided with a spiral passageway upon its inner side, the said passageways being in communication with each other, a plate located between said members and closing one side of each passageway, a pipe having communication with one of said members for supplying a fluid to the passageway therein, a discharge pipe having connection with the other of said members for conveying the fluid therefrom, and electrically heated coils located in contiguous relation to the outer sides of said members for heating the said members to heat the fluid as it flows from the said passageways.

4. A heating unit comprising a couple of members each of which is provided with a spiral passageway and with a depression at the center of its inner side with which the inner end of said passageway communicates, a plate between and in contact with said members which plate is provided with a central opening through which said depressions are in communication, means for delivering a fluid to the outer end of the passageway in one of the said members, means for discharging the fluid from the outer end of the passageway in the other of said members, means whereby the said members may be adjusted with relation to each other without interfering with the communication of the said spiral passageways with each other, and electrically heated coils located in contiguous relation to the outer sides of said members for heating a fluid as it flows through the said spiral passageways.

5. A heating unit comprising a plurality of disc-like members located in parallel spaced relation to each other, each of which is provided with a spiral groove upon its inner side, one end of each of which is lo-

cated adjacent to the periphery of a disc and the other end of each is located at the center of said disc, means common to the said members for closing one side of each groove 5 and for placing the said passageways in communication with each other at the center of the said disc-like members, a conduit for delivering a fluid to the outer end 10 of the passageway in one of said disc-like members, a conduit for conveying a fluid from the outer end of the passageway of the other of said disc-like members, and separate means located in contiguous relation to the outer sides of said disc-like members 15 for heating the said fluid as it flows through said passageways.

6. A heating unit comprising a couple of disc-like members located in parallel spaced relation to each other each of which is provided 20 with a spiral groove upon its inner side, the outer end of the groove in each disc-like member being located adjacent the

periphery thereof and the inner end of said groove being located at the center thereof, a plate located between the said disc-like members for closing one side of each of said grooves which plate is provided with an opening at its center whereby the inner ends of the passageways formed by the said grooves are placed in communication, means 25 for securing the said disc-like members and said plate together, means for delivering a fluid to the outer end of one of said passageways, electrically heated coils located in contiguous relation to the outer sides of the 30 said disc-like members for heating a fluid as it flows through the said spiral grooves, and means for conveying the fluid after it has been heated from the outer end of the other of said passageways. 40

In testimony that I claim the foregoing as my invention, I have hereunto signed my name this 16th day of December, 1924.

KARL MUHLEISEN.
